THERAPEUTIC VIBRATOR OR THE LIKE

Victor A. Kalish, Highland Park, Mich., assignor of fifty percent to Max Harley, Detroit, Mich.

Application February 11, 1959, Serial No. 54,556

Term of patent 14 years

(Cl. D83—1)

Fig. 1 is a perspective view of a therapeutic vibrator or the like showing my new design;

Fig. 2 is a left side elevational view thereof, the right side not shown being substantially the same;

Fig. 3 is a front elevational view thereof, the rear being substantially plain.

Fig. 4 is an enlarged fragmentary cross-sectional view thereof taken on line 4—4 of Fig. 1.

I claim:

The ornamental design for a therapeutic vibrator or the like, as shown and described.
